ROTARY KILN CHAIN ARRANGEMENT

William C. Johnson, Wauwatosa, Wis., assignor to
Allis-Chalmers Manufacturing Company, Milwaukee,
Wis., a corporation of Delaware

Application October 5, 1942, Serial No. 460,919

11 Claims. (Cl. 263—32)

This invention pertains to chain arrangements for rotary drums, and more specifically for rotary kilns.

While various chain arrangements for rotary kilns are known, most of such known arrangements utilize a plurality of chains which are fastened at their ends to the interior of the kiln, so that the intermediate portions only of the chains are effective in wiping the inner surface of the kiln to prevent building up mud rings therein. Such mud rings are objectionable in that they interfere with the flow of material and gases through the kiln, and seriously reduce the capacity of the kiln.

It is an object of this invention to provide a chain arrangement in which the chains are movable circumferentially or circumferentially and axially in their entirety, so that the complete length of each chain is useful in wiping the inner surface of the kiln.

It is a further object of this invention to provide a chain system in which each chain is loosely attached at its ends to a circumferential or helical bar adjacent the inner surface of the kiln and spaced therefrom, in such manner that the chain ends are free to slide along the lengths of such bars during rotation of the kiln.

In the drawing attached hereto:

Fig. 1 is a vertical sectional view of a kiln illustrating one embodiment of this invention, taken along the line I—I of Fig. 2;

Fig. 2 is a longitudinal section of the kiln taken along the line II—II of Fig. 1;

Fig. 3 is a longitudinal sectional view similar to Fig. 2, but illustrating a modification in which the chain supporting bars extend helically within the kiln; and

Fig. 4 is a fragmentary longitudinal sectional view similar to Fig. 2, but illustrating a modification in which the chains are arranged to overlap.

The drawing illustrates a standard kiln having a shell 10 provided with an inner lining 11, the feed end of the kiln being flanged at 12. In the modification shown in Figs. 1 and 2, a plurality of segmental circumferential bars 13 are arranged adjacent to the kiln lining, but spaced therefrom, the rods being supported in any suitable manner by means of radial supporting members 14, leaving each rod substantially unobstructed throughout its length. A plurality of slack chains 17 are mounted to extend between spaced bars 13, the chains being attached to the bars by means of rings 16 which are free to slide along the arcuate length of the bars. Material may be fed to the kiln by means of feed chute 18.

Serious problems have arisen in feeding material through a rotary kiln, particularly such wet materials as cement slurry. There is a tendency for the material to build up a "mud ring" in the kiln, thereby restricting the passage of material through the kiln. The resultant decrease in capacity has been only partially avoided by existing chain systems. Chain systems of the prior art have usually been fastened at one or both ends, so that while the intermediate portion of the chain may be useful in wiping along the surface of the kiln, the section of the kiln adjacent to the points of attachment of each chain has been substantially unaffected by the wiping action of the chains, so that mud rings were free to collect at those points.

In the chain system of this invention, however, as the kiln rotates the chains and their attaching rings tend to move to the lowermost part of the bars to which they are connected, as shown in Fig. 1. For example, at the left of Fig. 1 it will be noted that the chains are located at the trailing end of supporting bars 13, assuming the kiln is rotating in a clockwise direction. After the kiln has rotated through an angle such that the supporting bar has passed beyond its highest elevation it will be seen that, with the aid of gravity, the chain ends move along their supporting bars until they are located at the leading ends of the bars, so as to locate them in position to sweep the inner surface of the kiln after they pass the lowermost position. The chains, being heavier than the material handled, tend to break through the banked material, keeping it loose, and preventing objectionable adherence to the lining. Therefore a much more efficient action in keeping the inner kiln surface clean is brought about by this manner of attaching the chains. As the chains slide forward after passing the highest point, the rings, bars and chain ends also are cleared of any adhering material.

Fig. 3 illustrates a modification in which the chain supporting bars 13' extend helically within the kiln, rather than in a plane normal to the kiln axis. The result of this helical arrangement of the chain supporting bars is that as the chains slide from one end of their supporting bars to the other the chains move axially as well as circumferentially, thereby promoting a freer movement of the material within the kiln.

Fig. 4 illustrates a further modification, similar in some respects to that of Figs. 1 and 2, but in which the chains 17' are longer and attached to alternate bars, their middle portions passing between the intermediate bar and the lining of

the shell. Two chains 17' thus partially overlap, increasing the scraping action.

It is obvious that other flexible bands may be substituted for the chains referred to in the specification and claims, and are deemed to be included within the term "chains." The term "freely attached" as used in the claims is intended to define an attachment in which the chains are free to move along the lengths of their supporting bars.

The chain system described herein is illustrative only, the scope of the invention being limited only by the scope of the chains herein.

It is claimed and desired to secure by Letters Patent:

1. In a rotary cylindrical drum, a plurality of chains adjacent the interior surface of said drum, and means for attaching chains to said drum for free movement in their entirety along a substantial surface of the interior of said drum.

2. In a rotary cylindrical drum, a plurality of chains adjacent the interior surface of said drum and arranged approximately longitudinally thereof, and means for attaching said chains to said drum with considerable freedom of movement of the points of attachment of said chains circumferentially of said drum, whereby said chains are free to move in their entirety circumferentially within said drum during rotation thereof.

3. In a rotary kiln, bars of limited length supported within said kiln and spaced from the interior surface thereof, and a plurality of chains fastened to said bars for free movement along the lengths of said bars.

4. In a rotary kiln, bars of limited length supported within said kiln and spaced from the inner surface thereof, and a plurality of chains having their ends freely attached to said bars for free movement along the lengths of said bar.

5. In a rotary kiln, circumferential bars supported within said kiln and spaced from the inner surface thereof, and a plurality of chains each

freely attached to at least two of said bars which are spaced axially of said kiln, said chains being free to move at their points of attachment along the lengths of said bars.

5. 6. In a rotary kiln, a plurality of segmental bars within said kiln adjacent the inner surface thereof and spaced axially along said kiln, a plurality of chains within said kiln, each of said chains having each end freely attached to one of said bars for free movement along said bar, whereby said chains are free to move circumferentially in their entirety along the inner surface of the kiln during rotation thereof.

7. In a rotary kiln, a plurality of bars adjacent to the inner surface of said kiln and spaced therefrom, radial members supporting said bars within said kiln, a plurality of chains extending between certain of said bars, and rings slidable along the length of said bars connecting said chains to said bars, whereby said chains are free to move in their entirety circumferentially of said kiln during rotation thereof.

8. A structure as defined in claim 7, said bars being arranged in planes perpendicular to the axis of said kiln.

9. A structure as defined in claim 7, certain of said bars being arranged helically within said kiln, whereby said chains are free to move in their entirety in circumferential and axial directions within said kiln during rotation thereof.

10. A structure as defined in claim 7, each of said chains being attached to alternate bars, portions of said chains partially overlapping between certain adjacent bars.

11. A structure as defined in claim 7, said bars being arranged in planes perpendicular to the axis of said kiln, each of said chains being attached to alternate bars, the middle portion of each chain passing freely between an intermediate bar and said inner surface of said kiln.

WILLIAM C. JOHNSON.

CERTIFICATE OF CORRECTION.

Patent No. 2,332,724.

October 26, 1943

WILLIAM C. JOHNSON.

It is hereby certified that error appears in the printed specification of the above numbered patent requiring correction as follows: Page 2, second column, line 12, claim 6, for "entirely" read --entirety--; and that the said Letters Patent should be read with this correction therein that the same may conform to the record of the case in the Patent Office.

Signed and sealed this 7th day of December, A. D. 1943.

Henry Van Arsdale,

(Seal) Acting Commissioner of Patents.
